UNITED STATES PATENT OFFICE.

HARRY H. KRONE, MAX RUBINSTEIN, AND JACOB RUBINSTEN, OF CHICAGO, ILLINOIS.

GLASS-WASHER.

1,134,957.

Specification of Letters Patent.

Patented Apr. 6, 1915.

Application filed August 31, 1914. Serial No. 859,485.

To all whom it may concern:

Be it known that we, HARRY H. KRONE, a citizen of the United States, and MAX RUBINSTEIN and JACOB RUBINSTEN, subjects 5 of the Czar of Russia, and residents of the city of Chicago, county of Cook, and State of Illinois, have invented certain new and useful Improvements in Glass-Washers, of which the following is a specification.

10 Our invention relates to improvements in glass washers and has for its object the provision of an improved construction of this character capable of efficient and economical operation.

15 The invention consists in the combinations and arrangements of parts hereinafter described and claimed.

20 The invention will be best understood by reference to the accompanying drawings forming a part of this specification, and in which—

25 Figure 1 is a side view shown partially in section of a glass washer embodying our invention, Fig. 2, a top plan view of the same, Fig. 3, a section taken on line 3—3 of Fig. 4, and Fig. 4, a vertical section of the device.

30 The preferred form of construction as illustrated in the drawings comprises a hollow spraying head 5 adapted to pass within an inverted glass and provided with perforations at its upper end to direct sprays of water against the interior of said glass. Hollow spraying arms are extended outwardly from said spraying head and then curved upwardly and inwardly and adapted to direct sprays of water upon the outside of a glass resting over head 5.

35 A supporting table 8 is arranged around head 5 in position to support the lower edge of a glass 9 arranged over head 5.

40 An ornamental bell 10 extends downwardly from head 5 and a guide tube 11 is arranged therein. Guide tube 11 carries a 45 guide tube 12 telescoping a stationary guide tube 13 projecting upwardly and centrally from the bottom of a drain bowl 14 arranged as shown.

45 A water supply pipe 15 extends downwardly from head 5, is closed at its lower end and is provided with openings 16 arranged slightly above the lower end thereof.

50 A valve head 17 is arranged on the lower end of pipe 15 and co-operates with a valve seat 18 to control the flow of water from a water supply pipe 19 to the interior of sup-

ply pipe 15 and thence to the interior of head 5. Tube 15 also carries a valve head 20 slideable thereon and co-operating with a valve seat 21 to further seal the passage 60 against the escape of water when valve 17 is closed.

55 A compression spring 22 is imprisoned between valve 20 and head 5 and serves to maintain head 5 normally in elevated position and also to force valve head 20 to its seat. By this arrangement it will be observed that upon depression of valve head 5 openings 16 will be carried below valve head 20 and into the upper end of supply pipe 70 65 19 thus permitting a flow of water to head 5 and consequently to spraying openings 6 and spraying arms 7.

75 In use the glass is washed by simply placing the same over head 5 and depressing the same by pressure on the glass with the result above set forth. Upon removal of the glass the head 5 automatically rises to original position and the water supply is cut off thus conducing to economy in the 80 use of the water. The specific valve arrangement constitutes a simple and efficient one for the purpose and one which will not readily leak.

85 A perforated support 23 is arranged in the upper part of bowl 14 adapted to serve as a draining support for glasses and a drain pipe 24 leads from the bottom of bowl 14 to carry off the waste water.

90 While we have illustrated and described the preferred form of construction for carrying our invention into effect, this is capable of variation without departing from the spirit of the invention. We, therefore, do not wish to be limited to the precise details of construction set forth, but desire to avail ourselves of such variations and modifications as come within the scope of the appended claims.

95 Having described our invention what we claim as new and desire to secure by Letters Patent is:

1. A construction of the class described comprising a hollow depressible spring held head having spraying openings therein; a 105 water supply tube connected with the bottom of said head depending therefrom closed at its lower end and provided with valve openings adjacent said lower end; a valve head on the lower end of said pipe 110 co-operating with a valve seat to control the water supply; a valve head slideable on said

water pipe above said first mentioned valve head but normally below said valve openings and coöperating with a valve seat; and a spring surrounding said pipe and interposed between said slideable valve head and said first mentioned head, substantially as described.

2. A construction of the class described comprising a hollow depressible spring held 10 head having spraying openings therein; a water supply tube connected with the bottom of said head depending therefrom closed at its lower end and provided with valve openings adjacent said lower end; a 15 valve head on the lower end of said pipe coöperating with a valve seat to control the water supply; a valve head slideable on said water pipe above said first mentioned valve head but normally below said valve open-

ings and coöperating with a valve seat; a 20 spring surrounding said pipe and interposed between said slideable valve head and said first mentioned head; a bowl surrounding said water pipe; a perforated supporting member in the upper portion of said bowl; 25 and a drain pipe leading from the lower portion of said bowl, substantially as described.

In testimony whereof we have signed our names to this specification in the presence 30 of two subscribing witnesses.

HARRY H. KRONE.
MAX RUBINSTEIN.
JACOB RUBINSTEN.
